DESIGN FOR A SKIRT OR SIMILAR ARTICLE

Arthur Sternberger, New York, N. Y.

Application May 20, 1946, Serial No. 129,864

Term of patent 3½ years

(Cl. D3—26)

To all whom it may concern:

Be it known that I, Arthur Sternberger, a citizen of the United States of America, residing in New York city, county of New York and State of New York, have invented a new, original, and ornamental Design for a Skirt or Similar Article, of which the following is a specification, reference being had to the accompanying drawing, forming part thereof, wherein,

I claim:

The ornamental design for a skirt or similar article, substantially as shown.

ARTHUR STERNBERGER.
